UNITED STATES PATENT OFFICE.

WILLIAM D. GRAY, OF MILWAUKEE, WISCONSIN.

FLOUR-DRESSING MACHINE.

SPECIFICATION forming part of Letters Patent No. 278,702, dated June 5, 1883.

Application filed September 30, 1882. (No model.)

To all whom it may concern:

Be it known that I, WILLIAM D. GRAY, of Milwaukee, in the county of Milwaukee and State of Wisconsin, have invented certain Improvements in Flour-Dressing Machines, of which the following is a specification.

This invention relates to that class of machines which consist, essentially, of an inclosing case or body, a cylindrical reel revolving therein, and a series of blades or beaters revolving within the reel to drive the material under treatment against its interior surface, these machines being variously denominated in the art as "bran-dusters," "flour-dressers," and "centrifugal reels."

My invention relates to improved means for supporting and imparting a positive rotation to the horizontal revolving cylinder; to an improved manner of constructing said cylinder of segmental sections and intermediate connecting-bars; to a double reel consisting of two sections constructed and mounted upon a common axis, as hereinafter explained, and to various minor features of construction, which will be hereinafter enumerated in detail.

The accompanying drawings represent my improvements applied to both single and double machines.

Referring to the accompanying drawings, Figure 1 represents a longitudinal vertical section through the center of a single cylinder constructed on my plan, the upper half of the cylinder being shown in elevation and the lower half in section. Fig. 2 is an end elevation of the same. Fig. 3 is a transverse vertical section of the same, the left of said figure being on the plane $x x$, Fig. 1, while the right-hand portion of the view is on the line $y y$, Fig. 1. Fig. 4 is a longitudinal vertical section of a double-cylinder machine constructed on my plan, the upper half of the bolting cylinder or reel being shown in elevation, while the lower half is in section. Fig. 5 is a cross-section of the same on the line $z z$. Fig. 6 is a transverse section on the line $z z$, Fig. 3, through the lower side of the tail of the reel and one of its supporting and driving wheels. Fig. 7 is a face view of the parts illustrated in Fig. 5, separated from each other the better to show their form. Fig. 8 is a longitudinal vertical section through a portion of the head of the

reel and one of its sustaining-pulleys. Fig. 9 is a side elevation of the parts represented in Fig. 8. Fig. 10 is a plan view, illustrating the construction of the segments or sections of the bolting-reel and the casing in which they are connected one with another. Fig. 11 is a transverse section on the line $y y$ of Fig. 1, through one side of the bolting-reel, illustrating the construction and connection of its segmental sections; Figs. 12, 13, and 14, sectional views, illustrating the details of the reel.

Referring first to the single-cylinder machine represented in Fig. 1, A represents an external case or body sustained by a suitable frame-work, which may be of any form or construction adapted to inclose and sustain the working parts.

B represents the bolting cylinder or reel, extending lengthwise within the body and constructed and rotated in the peculiar manner hereinafter described.

C represents the main shaft, extending longitudinally through the center of the cylinder, sustained in bearings at the ends of the main frame, and provided within the reel with a series of arms or skeleton wheels carrying spiral blades or beaters D. By means of suitable driving devices, hereinafter detailed, the cylinder is gradually revolved, while at the same time the beaters are caused to revolve rapidly therein, in substantially the same manner as in other machines of this class common in the art. Heretofore the bolting-cylinder has been sustained in some instances by journals at its ends, and in others by friction pulleys or wheels, upon which the circular ends of the cylinder rested, and from which motion was communicated by frictional contact to the cylinder. In practice much difficulty has been encountered in the use of this frictional driving-gear because of the irregular motion imparted to the cylinder, and because of the uncertainty of its action in the presence of the dust which finds its way between the surfaces.

The object of the first part of my invention is to avoid this difficulty and cause the cylinder to be revolved positively and steadily without the objectionable tremulous motion commonly encountered; and to this end it consists in the combination of a cylinder, smooth-surfaced driving-pulleys, and toothed gear en-

gaging with corresponding surfaces and gear upon the reel, in the manner hereinafter explained in detail.

The cylinder may be driven by gear at one end only, sustained by the smooth-surfaced pulleys at the opposite end; or the driving-gear may be applied in the case of long cylinders to both ends, if desired, both constructions being represented in the accompanying drawings.

The manner of constructing and driving the cylinder when driven from one end only will be clearly understood on reference to Figs. 1, 3, 5, and 6. At each end the cylinder has a smooth cylindrical surface or flange, *a*. At the tail of the cylinder a circular geared ring, *b*, encircles the cylinder at the side of the smooth track or flange *a*.

The flange and teeth may be constructed separately and secured in position; but for the purpose of cheapness it is preferred to cast them both in one piece with the flange or hoop *C*, which constitutes the end of the cylinder-body. The smooth track or flange *a* is arranged to travel upon the corresponding smooth peripheral surfaces, *d*, of two pulleys or wheels, *E*, located on opposite sides of the machine, as shown in Fig. 3, at such distance apart as to admit of the cylinder resting between them. Each of the pulleys *E* has, in addition to the smooth surface *d*, a series of peripheral cog-teeth, *e*, which engage with the teeth *d* upon the cylinder. The surface *a* of the cylinder and the corresponding surfaces, *d*, of the pulleys are arranged to coincide with the "pitch-line" of the adjacent teeth, so that when the smooth surfaces of the cylinder and the smooth surfaces of the pulleys are brought together the teeth of the cylinder and pulleys will engage with each other and operate smoothly—in other words, the interlocking teeth will cause the smooth surfaces upon the cylinder and upon the pulleys to travel at equal speeds, so that the cylinder will roll upon the pulleys without slip and without sliding friction. In this manner the end of the cylinder is sustained firmly, carried smoothly, and caused to rotate with a positive action.

For the purpose of preventing the cylinder from moving endwise and causing the disengagement of the driving-teeth, the pulleys *e* are provided at the outer side with peripheral flanges *g*, which engage over the outside of the track *a*, as shown.

As regards the above arrangement for sustaining and driving the end of the cylinder, the essential feature of the invention consists in combining smooth sustaining-surfaces with driving-teeth, and it is manifest that the form and details of these parts may be modified in many respects, which will suggest themselves to the skilled mechanic, without essentially changing their mode of action or departing from the limits of my invention, and for this reason I do not restrict myself to the unessential details of form.

The head of the cylinder may be constructed and driven by appliances identical with those at the tail, as above described; but as I prefer in most cases to make use of a cylinder 70 having its head or a supplemental ring thereon adjustable longitudinally—as, for example, in Patent No. 260,477, July 4, 1882—for the purpose of stretching the bolting-cloth, I prefer to sustain the head of the reel, as shown in Figs. 1, 75 7, and 8, by means of pulleys, which admit of the cylinder being adjusted laterally thereon. Referring to this construction, it will be seen in Fig. 1 that the head of the cylinder, or a hoop forming its end, is provided with a smooth 80 peripheral flange, *a*, before mentioned, and that this flange rests upon and is sustained by two smooth-surfaced pulleys, *F*. These pulleys are made of a surface length or width sufficiently great to admit of the flange *a* being 85 shifted thereon a distance equal to that which the cylinder is moved in stretching the cloth.

In order to insure a steady motion of the cylinder, it is considered preferable to impart a positive rotation to the pulleys *F* as well as 90 to the driving-pulleys at the tail of the cylinder, and the means for so doing I will now describe. The corresponding pulleys, *E* and *F*, at opposite ends of the machine, are mounted upon horizontal shafts *G* and *G'*, which are 95 extended through the machine from end to end, and provided at one end with spur-wheels *H* *H'*, located outside of the body, as plainly represented in Figs. 1 and 2.

On the main or beater shaft *C*, which is the 100 main driving-shaft of the machine, a sprocket-wheel, *I*, is applied. Near the bottom of the machine a fourth sprocket-wheel, *J*, is mounted on a horizontal shaft, which also drives a conveyer, as hereinafter described. Around 105 the four wheels *H* and *H'*, *I* and *J*, a driving-chain, *K*, is passed, the single chain thus applied serving to transmit motion from the wheel *I*, through the wheels *H* and *H'* and their shafts, to the carrying-pulleys at both 110 ends of the cylinder, and also to the wheel *J*, by which the upper conveyer is driven. The upper conveyer, *L*, is mounted upon or attached to the shaft of the wheel *J*, and is extended horizontally through the base of the machine. Below the conveyer *L*, in the base of the machine, there is a second conveyer, *M*, separated from the one first named by an intermediate partition provided throughout its length with slides, by which the material may be 115 dropped through at any desired point from the upper to the lower conveyer, to be returned thereby. This arrangement of conveyers I do not claim.

The shaft of the upper conveyer is provided 120 with a gear-wheel, *N*, which engages with a corresponding wheel, *O*, applied to the journal of the lower conveyer.

It will be observed that under the above arrangement of parts positive motion is communicated to each and every moving part of the 130 machine, and that the driving-gear is all lo-

cated at one end of the machine. The cylinder or reel represented in Figs. 1, 2, and 3 is of ordinary construction, and is not claimed herein.

- 5 For the purpose of delivering the material into the cylindrical reel for treatment, a feed-spout, P, is provided at the head of the machine, as shown in Figs. 1 and 2. The fine material passing through the bolting-cloth is received by the upper conveyor, while the coarser materials, which pass over the surface of the cloth as tailings, are delivered through the open tail of the cylinder and descend through the passage Q to the lower conductor. 10
- 15 A slide, R, may be located at the base of this opening to permit the direct delivery of the material when desired.

For the purpose of permitting the proper passage of air-currents through the machine, 20 openings h may be made in the top casing and a large opening, I', provided in its end opposite the head of the cylinder. The inclined blades or beaters operate in connection with these openings to produce a draft or blast of air into the cylinder outward through its previous material. I prefer, however, in most cases to construct the cylinder in the peculiar manner hereinafter described, constituting an important feature of my invention. This 25

30 proved form of cylinder may be employed in place of that represented in Figs. 1, 2, and 3.

Referring next to the machine constructed with a double bolting-cylinder, reference is made to Fig. 4. It will be seen to consist, essentially, of an outside casing, A, a horizontal revolving slide, B, and a central main shaft, C, provided with a series of spiral beaters, D, as in the preceding apparatus. This second machine, however, is made of much greater 40 length than the one first described, and instead of having the cylindrical reel made in one continuous length to receive material at one end of the machine and discharge it at the other, it has a cylinder composed of two lengths or 45 sections, arranged end to end, with a space between them for the delivery of the tailings. The manner of building up the cylinder, forming the essential part of the invention, will be readily understood on reference to Figs. 4, 5, 50 10, 11, 12, and 13. Two annular hoops or rings, e e, are first provided to form the two ends. These rings are connected by a series of longitudinal metal bars, i, of T form in cross-section. These bars, of which there are 55 usually four, have the rib or flange cut away at each end for a short distance, as shown in Fig. 12, thus giving the bar two flat ends, which are secured rigidly to the inside of the respective hoops or rings by means of bolts j, 60 as clearly represented in the various figures. The longitudinal angle-bars and the end hoops secured together, as described, constitute a strong skeleton frame, to which the body portion of the cylinder is secured. This body 65 portion consists of a suitable number of segmental frames or sections, (represented in Fig.

10,) each consisting of a series of curved ribs attached at their ends to transverse connecting-bars, the whole constituting a segmental frame adapted to fit closely between two of the 70 longitudinal angle-bars i. These segmental sections are each made of a length slightly less than half the length of the cylinder. Each end of the cylinder-frame is completed by applying to the skeleton four of the segmental 75 sections, which are fitted between and against the angle-bars, and secured in place by bolts l, inserted through the angle-bars and these sections in the manner most clearly shown in Figs. 4 and 11. 80

In applying the segmental sections to the frame, care is taken to leave a space between the inner ends of the sections at one end of the cylinder and the inner ends of the sections at the opposite end of the cylinder, the space 85 thus left affording outlets through which the coarse material delivered in the two ends of the cylinder is permitted to escape. After bolting the segmental sections firmly in place, I apply the bolting-cloth to the inner surface 90 of the cylinder by nailing it fast to the interior of the wooden sections or in any other suitable manner, the central spaces, k, between the segments being left uncovered.

It will be seen that the cylinder constructed 95 as above described, although built with a single frame from end to end, constitutes in effect two independent cylinders adapted to receive material at their ends and to discharge the same at the center, or vice versa. The present machine is arranged to receive the material at the outer ends of the cylinders through feed-spouts S, provided for the purpose. The central space between the two ends or divisions of the cylinder is divided by a vertical 100 partition, thus producing two vertical passages, m, through which the tailings pass from the opposite ends of the cylinder to the respective conveyors located thereunder, there being a separate pair of conveyors under each 105 half of the cylinder. The conveyors for the two ends of the machine are mounted in line with each other upon common shafts, both of which shafts are operated from one end of the machine through a driving-gear operated from 110 the main shaft, the arrangement of the driving mechanism being identical with that represented in Fig. 2. The central space between the inner ends of the segmental sections may be left vacant, or segments may be introduced 115 between them for the purpose of giving additional rigidity and stiffness to the cylinder.

Owing to the great length of the cylinder used in this double machine, it is found advisable in most cases to drive the same from both 120 ends. This driving is effected by means of the combination and toothed rings with supporting and driving pulleys having the combination of smooth and toothed surfaces, as described in connection with the first machine, 125 and as represented in Figs. 6 and 7. The corresponding pulleys at the two ends of the ma-

chine are mounted upon one and the same shaft, the shafts being extended through the machine from end to end, as in the machine first described.

5 While I have described my method of building the frame of the cylinder as applied to a double reel, or reel having two independent end sections, it is to be distinctly understood that it is equally applicable to short cylinders, 10 such as shown in Fig. 1, in which case the segmental sections will extend continuously from one end of the cylinder to the other.

Owing to the great length of the beater-shaft C, there is a danger of its sagging slightly at 15 the center, and consequently binding in the bearings at its ends. In order to avoid difficulty from this source, I sustain the shaft in boxes o, which have spherical outer ends seated in corresponding recessed supports or bearings, 20 p. This construction permits the boxes to rock or tip in their bearings to accommodate themselves to the varying position or inclination of the shaft, thus permitting the shaft to run freely at all times. The boxes o are usually 25 divided lengthwise into equal parts, and the bearing p constructed with a movable cap or top piece secured in place by bolts to permit the introduction and removal of the box. It is also preferred to provide the parts of the 30 box with longitudinal ribs or lugs engaging in corresponding grooves in the bearing d, to prevent the box from rotating therein.

As regards the construction of the cylinder-frame, the improvement consists, essentially, in 35 combining with the hoops or end rings the longitudinal bars connecting them and the segmental frame-sections bolted to and sustained by the bars. So long as this construction is substantially adhered to, the details 40 may be modified as desired.

It will of course be understood that when 45 the cylinder is constructed with the longitudinal bars bolted to the end rings or hoops the head of the cylinder cannot be adjusted to effect the stretching of the bolting-cloth. If it be desired to secure this adjustment, a separate 50 movable ring or hoop must be applied to the end of the frame, or the connection of the hoop at one end of the longitudinal bars must be a sliding one to admit of the hoop being moved. The last-named construction, although not desirable in ordinary cases, is indicated on the 55 right-hand side in Fig. 12, in which it will be seen that the longitudinal bar is slotted to allow a limited play of the bolts by which it is connected to the hoop forming the head of the cylinder.

It will be perceived that the machine constructed as shown in Fig. 4 constitutes in effect a 60 duplex machine, or machine containing two combinations of mechanism, which effect the bolting operation independently of each other. The machine constructed in this manner possesses many advantages where a large amount 65 of work is to be performed, the principal advantages being the economy of space, the re-

duction in the cost of construction as compared with separate machines of equal capacities, and the reduction of the working parts to the smallest number possible.

70 While I have in the drawings represented the double machine arranged to receive the material at the heads of the cylinder and discharge the same at the center, the feeding-spouts may, if preferred, be located at the center and the tailings delivered at the ends, in which case it will only be necessary to reverse the motion of the conveyers, and to give the beaters and blades an obliquity in the opposite direction from that shown in the drawings, to effect the feeding of the material toward the ends, instead of toward the center.

Having thus described my invention, what I claim is—

1. The revolving reel or cylinder provided 85 with the smooth cylindrical and the toothed surfaces encircling the same, in combination with supporting-pulleys provided with corresponding smooth and toothed surfaces.

2. A horizontal bolting-reel encircled by a 90 smooth track or flange, and also by a line of gear-teeth, in combination with a wheel provided with teeth engaging with teeth of the reel, and also with a smooth supporting-surface bearing beneath the track or flange of the 95 reel, substantially as described and shown, whereby said pulley is adapted to serve the twofold purpose of supporting and driving the reel.

3. In combination with the bolting reel or 100 cylinder having the flange a and teeth b, the supporting driving-pulleys provided with the teeth e, surfaces d, and flange g, as and for the purpose described.

4. The reel having the smooth encircling 105 track or bearing a and adjacent teeth b, combined with the supporting-pulleys provided with corresponding smooth surfaces and teeth, the smooth surfaces on both the reel and the pulley coinciding with the pitch-lines of the gear-teeth, whereby the two smooth surfaces are caused to travel at equal speeds without slip or friction upon each other.

5. The bolting-reel provided with smooth 115 encircling tracks or flanges and gear-teeth at both ends, in combination with two longitudinal shafts and two supporting and driving pulleys, mounted on each shaft and located beneath opposite ends of the reel, each pulley having a smooth supporting-surface and a series of driving-teeth, as described and shown, whereby a smooth positive motion is imparted to both ends of the reel.

6. The metallic ring or hoop forming the 125 head of the bolting-cylinder, provided with the smooth flange a and teeth b, in combination with the driving and supporting pulley E, provided with a smooth surface, d, and toothed surface e.

7. In combination with a bolting-reel and 130 devices, substantially such as shown, for sustaining the same and preventing its longitudi-

nal motion, a smooth encircling flange applied to the opposite end of said reel, and a sustaining-pulley for said flange, having its surface adapted, as described, to permit the adjustment of the flange thereon in the direction of the axis of the pulley.

8. A bolting reel or cylinder having one end or head movable in the direction of its axis for the purpose of stretching the bolting-cloth, in combination with an encircling flange or track thereon and smooth supporting-pulleys beneath said flange, said pulleys having widened or extended surfaces, as described, to permit the movement of the flange thereon as the head of the reel is adjusted.

9. In combination with a horizontal bolting reel or cylinder, supporting-rolls located beneath its opposite ends, the rolls at one end being flanged and arranged to engage with a corresponding flange upon the reel to prevent the longitudinal motion of the latter, and the rolls at the opposite end being made with smooth extended surfaces adapted to permit the end of the reel to slide lengthwise thereon.

10. In combination with the bolting-reel, the supporting and driving pulleys, constructed as described, and located beneath one end of the same, the smooth supporting-pulleys located beneath the opposite end of the same, and the driving-shafts G, extended endwise through the machine, and each provided with pulleys at both ends of the reel, as and for the purpose described.

11. In a flour-dressing machine, the combination of the reel, the beaters, the pulley on the beater-shaft, the pulley on the conveyer-shaft, the two pulleys upon the respective shafts of the reel, driving and supporting rolls, and a single chain or belt, K, engaging with the four pulleys, as and for the purpose described.

12. In a flour-dressing machine, the combination of the horizontal reel, the beater-shaft,

the rolls sustaining said reel, and gearing, substantially as described, connecting said rolls 45 with the beater-shaft.

13. The combination of the beater-shaft, the bolting reel or cylinder, the two shafts provided with pulleys sustaining said reel, and a single driving-chain extending from a pulley 50 on the beater-shaft to pulleys upon the two roller-shafts, as described, whereby motion is communicated from the beater-shaft through a single connection to all the supporting-rolls of the reel.

14. In combination with the bolting-reel and the rotary spiral beaters therein, the inclosing case or body A, provided with the end opening for the admission of air, and with the top opening, h, to permit the escape of the same, 60 whereby a continuous outward draft is produced through the bolting-surface during the action of the machine.

15. In a bolting-reel, the combination of two end hoops or rings, a series of longitudinal 65 ribbed bars of T form, having flat ends extended beyond the ribbed portion, said ends being applied and bolted to the inner surface of the rings with the ribs extending outwardly, as described and shown.

16. In a bolting-reel, the two end hoops, the longitudinal ribbed bars having their ends flattened and bolted to the inner surface of the hoops and the ribs presented outward, in combination with the segmental cloth-covered 75 frames applied externally to the ribs and hoops and secured thereto, as described and shown.

17. In a flour-dressing machine, the combination, with the beater-shaft, of the boxes, of spheroidal form, mounted loosely in bearings, 80 substantially such as described and shown.

WILLIAM DICKSON GRAY.
